UNITED STATES PATENT OFFICE.

HENRY HOWARD, OF CLEVELAND, OHIO, ASSIGNOR TO THE GRASSELLI CHEMICAL COMPANY, OF CLEVELAND, OHIO, A CORPORATION OF OHIO.

REPORT.

Application filed June 15, 1923. Serial No. 343,668.

To all whom it may concern:

Be it known that I, HENRY HOWARD, a citizen of the United States, residing at Cleveland, in the county of Cuyahoga and State of Ohio, have invented certain new and useful Improvements in Retorts, of which the following is a specification.

This invention relates to apparatus and more particularly to a distilling vessel or retort for the distillation or concentration of liquids such as corrosive acids, for example sulfuric acid, hydrochloric acid and the like.

In an application filed May 29, 1922, in the names of Glenn A. Keep and Clayton M. Hoff, Serial No. 564,512 there is disclosed apparatus and process for the distillation of liquids such as hydrochloric acid solutions. One of the principal features of the invention described in that application is the heating of the liquid to be distilled by the passage of electric current therethrough. The apparatus disclosed in said application comprises a retort formed of non-conducting refractory material such as porcelain, earthenware or the like.

The present invention relates to an improved retort for the carrying out of processes such as that described in said Keep and Hoff application.

The invention resides in a retort formed of natural stone which is impervious and refractory to corrosive liquids such as hot strong mineral acids. The preferred natural stone for the construction of the retort is granite and more particularly that kind of granite known as Quincy granite. Any stone of similar properties in relation to hot hydrochloric acid solution may be used.

The invention will be described and illustrated hereinafter with reference to the heating and distillation of hydrochloric acid solutions by the passage of electric current therethrough in a retort formed of granite illustrated in the accompanying drawings in which—

Fig. 1 is a perspective view of the retort and its supporting structure and the distillate condenser;

Fig. 2 is a plan view of the top of the retort;

Fig. 3 is a side elevation of the retort with parts broken away, and

Fig. 4 is a vertical transverse section on the line 4—4 of Fig. 3.

Referring to the drawings, A is the retort and B the condenser. The retort consists of the upper part 1 and the lower part 2, both hollowed out to form the chamber C. The joint between the two parts 1 and 2 is made liquid tight by means of a suitable packing in the groove 3. That part of the chamber C formed by the lower part 2 of the retort is in the shape of a shallow rectangular receptacle having a flat bottom with transverse wells 4 at its opposite ends. The shape of the left hand end of the chamber C which is hidden in Fig. 3 is the same as the shape of the right hand end illustrated in Fig. 3. The opening 5 in the lower part 2 of the retort is connected with the pipe 6, the joint being made liquid tight by the rubber stopper or packing 7. Pipe 6 is for the discharge of residual liquid from the retort. The top 1 of the retort has an opening 8 connected with the liquid supply pipe 9, the joint being made gas tight by the rubber stopper or packing 10. The upper part 1 of the retort also has an opening 11 connected with the distillate discharge pipe 12 leading to the condenser B, and openings 13 positioned over the wells 4 for the electrodes 14. The joints between the pipe 12 and the electrodes 14 with the respective openings are made gas tight by means of suitable packings. As is illustrated in Fig. 1 the two parts 1 and 2 of the retort are held in position and supported by a suitable frame work.

For the distillation of liquid, say hydrochloric acid solution, in the apparatus illustrated the liquid to be distilled is supplied through the pipe 9. Vapor passes through the pipe 12 to the condenser B and residual or undistilled acid is discharged through the pipe 6. The supply of acid to be distilled and the discharge of residual acid are regulated with respect to each other and the rate of distillation so as to maintain the desired depth of acid in the chamber C. The rate of distillation is regulated by variation of the depth of acid in the chamber C over the flat bottom between the electrode wells 4 and by variation of the flow of electric current, thus varying at will the current density in the liquid and consequently the rate of heating and distillation.

Attempts have been made to use a variety of materials for the construction of the retort. Sandstone which is more or less ex-

tensively used for the construction of receptacles for hydrochloric acid has been found to be so porous that it soon becomes a conductor of electricity due to absorption of acid rendering it unfit for further use. The impregnation of the sandstone with various materials such as tar and pitch to render it non-porous is unsatisfactory due to the resultant contamination of the acid. Earthenware retorts may be used but are not at all satisfactory. They crack or break after a relatively short period of use, apparently due to their deficiency of resistance to thermal strains.

15 Retorts formed of Quincy granite have been found to give very satisfactory results. The material is a non-conductor of electricity and is non-porous and even after long continued use shows no tendency to crack or leak or become conductive or even to corrode materially. Although Quincy granite has been used in the past in places where it was exposed to the action of cool hydrochloric acid, it was not to be expected that it would withstand the corrosive action of hot acid for any long period of time. On the contrary, it was expected that it would corrode and disintegrate. The finding that it stands up very satisfactorily therefore is quite surprising.

20 In the foregoing specification I have referred particularly to the distillation of hydrochloric acid by electrical heating. It is however apparent and is to be understood that the invention, i. e. the use of a retort formed of natural stone such as Quincy granite, is not limited to the distillation of hydrochloric acid or to electrical heating. Any other suitable method of heating, for instance, by means of electrically heated resistance elements or conduits immersed in the liquid and carrying a heating fluid, may be employed and other liquids such as sulfuric acid, nitric acid, acetic acid, etc., 25 may be heated or distilled without departure from my invention.

I claim:

1. A retort for the distillation of corrosive liquids formed of non-conductive, impervious and acid-resistant natural stone.
2. A retort for the distillation of corrosive liquids formed of Quincy granite.
3. A retort for the distillation of corrosive liquids comprising a block of non-conductive, impervious and acid-resistant stone having a recess in one face thereof and a closure for said recess formed of non-conductive, impervious and acid-resistant natural stone.
4. A retort for the distillation of corrosive liquids consisting of two blocks of non-conductive, impervious and acid-resistant natural stone, each having a recess in one face thereof and adapted to fit together with said recesses in communication forming a chamber.
5. A retort for the distillation of corrosive liquids as defined in claim 3 in which the natural stone is Quincy granite.
6. A retort for the distillation of corrosive liquids as defined in claim 4 in which the natural stone is Quincy granite.
7. A retort for the distillation of hydrochloric acid comprising a lower block of Quincy granite having a recess in its upper face, said recess having a shallow central region and deeper end regions, an upper block of Quincy granite having a recess in its lower face, said upper block being shaped to fit onto said lower block with said recesses in communication forming a chamber, openings in said upper block positioned above the deeper end regions of the recesses in said lower block adapted to receive electrodes; a liquid supply opening in said upper block, a liquid discharge opening in said lower block and a distillate discharge opening in said upper block.

In testimony whereof, I affix my signature.

HENRY HOWARD.
